UNITED STATES PATENT OFFICE.

LESLIE CARROLL HOLLINGSHEAD, OF CHICAGO, ILLINOIS.

BARREL-HOOP.

1,286,635.

Specification of Letters Patent.

Patented Dec. 3, 1918.

Application filed July 24, 1918. Serial No. 246,575.

To all whom it may concern:

Be it known that I, LESLIE CARROLL HOLLINGSHEAD, a citizen of the United States, and a resident of Chicago, in the county of 5 Cook and State of Illinois, have invented certain new and useful Improvements in Barrel-Hoops, of which the following is a specification.

My invention relates to improvements in 10 barrel hoops, and it consists substantially in the construction and arrangement herein described and claimed.

An object of my invention is to provide a 15 barrel hoop shaped in such a manner as to conform to the tapering shape of a barrel, thereby securing a contact between the surface of the barrel and the entire width of the hoop and avoiding the leaving of a space between the barrel and the upper part of 20 the hoop as is usually the case and more especially so when using wooden hoops.

A further object of the invention is to 25 provide a metallic barrel hoop, initially shaped to conform to the shape of the barrel, thereby eliminating the extra operation of flaring the hoop, as it is necessary to do with metallic hoops such as are at present on the market.

A further object of the invention is to 30 provide a barrel hoop having the important features above enumerated, which is provided with suitable interlocking means whereby the hoop can be fitted together by simply slipping one end into the other and 35 adjusting it to the proper diameter, thereby eliminating the riveting operation necessary in making metallic hoops.

Other objects and advantages will appear 40 in the following specification, reference being had to the accompanying drawing in which:

Figure 1 is a perspective view of the upper portion of a barrel showing two of the improved hoops applied,

Fig. 2 is a perspective view of one of the 45 hoops before adjustment,

Fig. 3 is a detail perspective view showing more clearly the construction of the ends of the hoop,

Fig. 4 is a longitudinal section taken substantially on the line 4—4 of Fig. 1,

Fig. 5 is a cross section on the line 5—5 of Fig. 3,

Fig. 6 is a cross section on the line 6—6 of 55 Fig. 3,

Fig. 7 is a detail perspective view showing the ends of the hoops perforated for rivets, and

Fig. 8 is a perspective view showing the two ends riveted together.

As has already been stated, one of the foremost objects of the invention is to provide a barrel hoop that will lie in close contact with the sides of a barrel throughout the width of the hoop and thus avoid the 60 space at the top which is usually left when wooden hoops are used. Therefore in order to carry out the invention, I provide a hoop 1 which is made of metal.

Originally, the hoop consists simply of a 70 metal band which is bent over into the shape illustrated in Fig. 5. Here it will be seen that in cross section, the hoop 1 has a vertical outside 2 and an inclined inside 3. This shape is gotten by bending over the bridge 75 portion at the top and causing the edges of the band to meet at the bottom. The inclined inside 3 conforms to the slanting shape of the barrel 4, and therefore the hoop 1 lies in close contact with the surface 80 of the barrel as plainly shown in Fig. 1.

The hoop is hollow on the inside as obviously it must be by the manner of construction which is employed. This construction permits the fitting of one end of the hoop 85 into the other to form a continuous circle. To this purpose, the insertible end 5 is crimped along the bridge piece at 6, for a distance substantially equal to the extent of a plurality of slots 7^a on the inside inclined 90 wall 3.

By crimping the bridge piece as shown, the width of the insertible end 5 is sufficiently reduced to enable it to be fitted into the receiving end 7 of the hoop, on the inside wall 3 of which a plurality of tongues 8 are stamped inwardly to interlock with the slots on the insertible end. In practice, the barrel hoop is made by simply fitting the end 5 into the receiving end 7 and adjusting it 100 over the tongues 8 until the proper diameter is reached.

The slots 7^a interlock with all of the tongues 8 that come into proper registration. The formed hoop is then fitted over the barrel, driven in place and secured by any suitable means. The bridge which is naturally located at the top of the hoop, forms a convenient driving edge in driving the hoop in place. It should be observed that another 110

feature of importance lies in the fact that this hoop is initially formed in the shape illustrated, at the mill.

There are metallic hoops on the market which when used as originally formed, offer the same objections that are present in using wooden hoops, *i. e.*, the leaving of a space at the top and the consequent uneven fitting of the hoop on the barrel. The former objection being present, requires the extra operation of flaring the hoop so as to give it the proper shape. It will at once be obvious that a hoop made in accordance with my invention overcomes the objections above stated and at the same time, makes the hoop much stronger because of the presence of the extra outside wall.

The riveting together of the ends of the hoop is entirely dispensed with in the preferred construction, but there are instances which shall presently be referred to, wherein the automatic locking device in the ends of the hoop may be eliminated and rivets may be employed. However, in the preferred construction, the arrangement of the slots 7^a and tongues 8 is such that a sufficiently fine adjustment can be gotten to enable the compensation for any slight variation in the diameter of the barrel in the region wherein the hoop is to be applied, in making up the hoop.

It need hardly be stated that the operation of forming the hoop by simply slipping the ends together, is considerably more simple than to rivet the ends together as is now usually the practice. Consequently, many more hoops can be formed by employing the preferred manner of making the hoop, than is possible with the methods now employed.

The circumstance above referred to, wherein the automatic locking device is eliminated, is one wherein it is proposed to simply lap the insertible end 5 over the receiving end 7 or vice versa, and then rivet 45 the two together by means of the rivets 8^a as shown in Fig. 8.

While the construction and arrangement of the hoop herein described is that of a generally preferred form, obviously slight modifications and changes may be made without departing from the spirit of the invention or the scope of the claims.

I claim:

1. A tubular barrel hoop, formed into a substantially triangular shape to provide a driving edge at the top and an inclined inner wall to fit the barrel, one end of the hoop being constricted by crimping, to fit into the other end, and engageable locking tongues and slots on the inner walls of both hoop ends, forming a lock invisible from the outside and avoiding exposed projecting parts.

2. A barrel hoop, comprising a bent metal band having an inclined inside wall to conform to the shape of a barrel and insure a contact throughout the width of the hoop, one end of the hoop being arranged to be fitted inside of the other in forming the hoop, and means embodied in both ends enabling the automatic locking thereof to the adjusted position.

3. A barrel hoop, comprising a metallic band bent to form a vertical outside wall, a bridge at the top providing a driving edge 75 for the hoop, and an inclined inside wall to fit the shape of a barrel, the edges of the band meeting at the bottom thus forming a hollow hoop; the receiving end having a plurality of inwardly stamped tongues on 80 the inside wall, the insertible end having a plurality of cooperating slots on the inside wall, with a longitudinal crimp in the bridge to enable the fitting of one end into the other.

4. A hoop, consisting of a body having a 85 vertical outside wall, an inclined inside wall adapted to conform to the shape of a barrel and meeting the outside wall at the bottom edge, the upper edge of the hoop being relatively broad to form a driving edge.

LESLIE CARROLL HOLLINGSHEAD.
